UNITED STATES PATENT OFFICE.

ADRON J. BROOKBANK, OF HUNTINGTON, WEST VIRGINIA.

MENU-CARD AND NAPKIN HOLDER.

Application filed February 27, 1924. Serial No. 695,473.

To all whom it may concern:

Be it known that I, ADRON J. BROOKBANK, a citizen of United States, residing at Huntington, W. Va., have invented certain new and useful Improvements in Menu-Card and Napkin Holders, of which the following is a specification.

This invention relates to menu card and napkin holders for restaurants and has special reference to a combined device arranged to display plainly the menu cards for a restaurant on a table and at the same time to support a bundle of the usual paper napkins. The device may also be used, if desired, as a flower stand.

One important object of the invention is to improve the general construction of a device of this character.

A second important object of the invention is to provide an improved device of this character wherein a single bolt is used to hold the card support in a freely revoluble manner and the napkin holder or flower vase fixed thereabove.

A third important object of the invention is to provide an improved ball bearing arrangement for such a device.

With the above and other objects in view as will be hereinafter apparent, the invention consists in general of certain novel details of construction and combinations of parts hereinafter fully described, illustrated in the accompanying drawings and specifically claimed.

In the accompanying drawings like characters of reference indicate like parts in the several views, and:

Figure 1 is a plan view of the complete device.

Figure 2 is a side elevation thereof.

Figure 3 is an enlarged detail section, partly broken away and taken on the line 3—3 of Figure 2.

Figure 4 is an enlarged detail section on the line 4—4 of Figure 2.

Figure 5 is an enlarged detail edge view of one of the card holders, illustrating in dotted lines the manner in which the card frames are inserted and removed, the view being taken in the direction of the arrows on the line 5—5 of Figure 2.

The invention, in the present embodiment, comprises a base 10 having a centrally disposed opening 11 therein, the base being hollow on its underside for purposes which

will be presently understood. Extending up through the opening 11 is the main securing bolt 12 which holds the card support and napkin or flower vase together, the lower end of this bolt is threaded and screwed thereon is a nut 13 having its upper end tapered to form a lower inner ball race. Thus nut 13 also acts as a clamp nut on the upper side of the hollow base 10 while a second nut 14 and washer 15 on the lower end of the bolt 12 beneath the top of the hollow base 10 fixes the bolt firmly to the base. The upper end of the bolt 12 is in like manner threaded and is provided with nut 16 similar to the nut 13 but in inverted position. This upper nut also has a tapered end, which in this case forms an upper inner ball race. Surrounding the bolt 12 between the two nuts 13 and 16 is a tubular post or support 17 having at each end an inwardly projecting flange 18 forming an outer ball race, balls 19 being located between the respective inner and outer ball races. With this construction adjustment of the nut 16 adjusts both of the ball bearings thus formed. At each end of the tube 17 there is provided an outwardly extending flange 20 and from each flange 20 there extends an annular rib 21 terminating in an inwardly extending flange 22 which closely encloses the respective nut 13 or 16 and acts as a guard for the balls. Secured to each of the flanges 20 is an annular plate 23, ordinary bolts 24 being used for this purpose.

The plates 23 serve to support the card holding frames 25 and each of these card holding frames 25 consists of a U-shaped rod, the terminals of which are split and rabbeted to fit over the respective plate 23, being held thereon by the bolts 24 and also by bolts 26. On each of the horizontal legs of these frames there is provided a card frame clip which consists of a thin plate of metal so bent to U-shape as to provide an arcuate body portion 27, which fits on the respective horizontal leg of the frame 25 and has extending therefrom edge portions 28 and 29, the latter being of greater width than the former as can clearly be seen in Figure 4. The card frames consist of rectangular metal frames the sides and bottoms of which are channel-shaped as indicated at 30 in Figure 4, while the top consists of a pair of spaced sides 31 so that a card 32 and

cover plates 33 of celluloid or other thin transparent material may be slipped in and out of the frame at will. These frames are of such size that the top and bottom of each 5 frame engages between the upper and lower clips 27 and in order to insert or withdraw a frame it is merely necessary to tilt the respective clip as shown in the dotted line position in Figure 5 thus freeing the card 10 frame from the supporting frame 25.

On top of the nut 16 there is provided a washer 34 above which is a lock nut 35. Screwed on the upper end of the bolt 12 above the nut 35 are confronting nuts 36 15 each cooperating with a washer 37 to clamp the bottom plate 38 of an inverted frusto-conical napkin or flower holder 39, the bolt 12 passes through said bottom for the purpose. This flower holder has a skirt 40 extending downwardly so as to surround the upper nuts locked between the top of the tube 17 and said bottom and thus conceal them from view.

It will be seen by this construction the 25 holder 39 is held on the top of the bolt and that by removing the upper nut 36 the holder 39 may be lifted off the bolt and then by removing the lower nut 36 and the nuts 35 and 16 the entire device may be 30 assembled. It will also be seen that the holder 39 constitutes a vase.

There has thus been provided a simple and efficient device of the kind described and for the purpose specified.

35 It is obvious that minor changes may be made in the form and construction of the invention without departing from the material spirit thereof. It is not, therefore, desired to confine the invention to the exact 40 form herein shown and described, but it is desired to include all such as properly come within the scope claimed.

I claim:

1. The combination with a base; of a bolt, having its lower end secured to said base 45 and extending upwardly therefrom, spaced inner ball races screwed on said bolt above said base, a tubular support surrounding said bolt between said ball races and having inwardly projecting flanges at its ends, said 50 flanges constituting outer ball races co-operating with said inner ball races, balls between the respective co-operating races, external flanges at the ends of said tubular support, an annular plate carried by each 55 of said flanges, and U-shaped frames having the ends of their legs split to embrace said plates and secured thereto, and card frames detachably mounted in said U-shaped frames.

2. The combination with a base; of a bolt having its lower end secured to said base and extending upwardly therefrom, spaced inner ball races screwed on said bolt above said base, a tubular support surrounding 60 said bolt between said ball races and having inwardly projecting flanges at its ends, said flanges constituting outer ball races co-operating with said inner ball races, balls between the respective co-operating races, 65 radial card supporting frames carried by said support, and a means removably mounted on the upper end of said bolt and provided with a depending skirt concealing the upper ball bearing.

3. In a device of the kind described, a card supporting frame having upper and lower members, substantially U-shaped clips surrounding said members in confronting relation and movable therearound, and a 70 card frame having its top and bottom portions engaged between respective clips.

In testimony whereof I affix my signature

ADRON J. BROOKBANK.
